UNITED STATES PATENT OFFICE

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT

HOOD CATCH

Original application filed June 17, 1926, Serial No. 116,530. Divided and this application filed August 8, 1928. Serial No. 298,290.

The present invention relates to automobile hood catches, particularly of the type adapted to exert both a downward and an inward pressure on the hood, for the purpose of securely holding it in closed position without looseness and rattling, the present application being a divisional application of my former application filed on the 17th day of June, 1926, Serial No. 116,530.

10 Another object is to provide a catch structure in which the usual spring actuated hood catch or hook element acts downwardly to hold the hood downwardly against the frame of the automobile and in which means acting 15 between the keeper and the hood catch barrel exerts a lateral pressure between the hood and barrel to press the hood inwardly.

A further object is to provide a catch including movable means carried by the keeper, 20 adapted to produce, through the single directional force of the spring actuated hook, a plurality of pressure components adapted to act upon the hood to force it downwardly and inwardly.

25 With the above and other objects in view, embodiments of the invention are shown in the accompanying drawings, and these embodiments will be hereinafter more fully described with reference thereto, and the invention 30 will be finally pointed out in the claims.

In the drawings:—

Fig. 1 is a perspective view of the hood catch keeper according to one embodiment of 35 the invention;

Fig. 2 is a side elevation showing the same with the hood catch hook element in operative engagement therewith;

40 Fig. 3 is a perspective view of another modified form of keeper;

Fig. 4 is a side elevation showing the same with the hood catch hook element in operative engagement therewith;

45 Fig. 5 is a perspective view of a further modified form of keeper; and

Fig. 6 is a side elevation showing the same with the hood catch hook element in operative engagement therewith;

50 Similar reference characters indicate cor-

responding parts throughout the several figures of the drawings.

Referring to the drawings, the hood catch hook element consists of a cylindrical barrel 20 flanged at its lower end, as at 21, to provide a reduced passage in which a rod 22 is slidably engaged, the end of the rod within the barrel being provided with a head 23, between which and the flange 21 a spring 24 is coiled about the rod.

The upper end of the barrel is threaded, as at 25, and is screwed into the threaded socket 26 of a cap member 27, which closes the upper end of the barrel and forms a stop to limit the upward movement of the rod 22 under the pressure of the spring. A clamping hook 28 and a handle 29 are formed integrally with the cap member.

At its lower end the rod is provided with a rounded enlargement or head 30, received within a flanged substantially semi-spherical socket member 31 secured to the automobile frame 32 by suitable rivets or screw bolts 33, the opening 34 in said socket member to receive the rod being in the form of a slot elongated in a direction at right angles to the side of the hood.

The hood 35, which in its closed position is engaged against a stop flange 36 secured to the frame, is provided with a keeper for engagement of the hook 28 to draw the hood downwardly toward the frame under the pressure of the spring 24, the keeper, according to the invention, being further adapted through said downward pressure to produce an inward pressure upon the hood acting between the hood catch barrel and the hood.

The keeper, according to the embodiment shown in Figs. 1 and 2, comprises a base plate 37 adapted to be riveted to the hood, provided at its vertical side edges with forwardly bent ears 38—38 and at its lower edge with a forwardly bent abutment flange 39. A bell-crank lever 40 having forwardly extending side portions 41—41 is provided at its upper portion with a transverse tubular bearing 42, preferably bent therefrom, and pivotally mounted between the ears 38—38 by means of a transverse pin 43. A transverse bar 44 is secured between the forward ends of

55

the side portions 41 and is adapted for engagement by the hood-catch hook 28, and at the lower end of the lever there is hingedly connected, as at 45, a pressure arm 46 adapted to abut the flange 39 at a point intermediate its ends, and provided at its lower end portion with a forwardly bent rounded contact portion 47, for engagement with the hood catch barrel.

10 In operation the hook 28 is engaged over the transverse bar 44 of the bell-crank lever, and under the action of the spring 24 the lever is rotated to swing its lower end inwardly, which through abutment of the arm 15 46 with the flange 39 presses the contact end portion 47 of said arm 46 outwardly against the hood catch barrel, thereby pressing the hood inwardly and holding it under pressure against looseness and rattling, the hood at the 20 same time being pulled downwardly by the downward pull of the hood catch.

In Figs. 3 and 4 I have illustrated another modification, in which the keeper comprises an elongated base plate 48 riveted to the hood, provided at its vertical side edges and near its upper end with forwardly bent ears 49—49 supporting a transverse pin 50, upon which there is pivotally mounted a lever member comprising side arms 51—51 and a transverse connecting portion 52. The side arms are rounded at their lower rearward edges to permit downward swinging movement and are angular at their upper rearward edges to provide movement limiting abutment portions, a spring 53 coiled about the pin 50 and bearing at its respective ends upon the base plate and the connecting portion 52 adapted to normally retain the lever member in its raised position, as indicated in Fig. 3.

40 A transverse pin 54 is provided between the outer ends of the arms 51—51, upon which is hingedly secured the upper end of an angular depending lever arm 55, curled at its lower end, as at 56, and engaging a beveled cam portion 57 provided upon the lower end of the base plate 48. A resilient bumper 58, formed of rubber, or the like, is secured upon the forward side of the lever arm adjacent the curled end 56, and is adapted to engage 50 the barrel of the hood catch.

In operation the hook 28 is engaged over the transverse pin 54 of the lever member, causing the arm 55 to move downwardly and outwardly upon the beveled cam portion 57 and tightly pressing against the hood catch barrel, thereby pressing the hood inwardly and holding it under pressure against looseness and rattling, the hood at the same time being pulled downwardly by the downward pull of the hood catch.

In Figs. 5 and 6 I have illustrated a further modification, in which the keeper comprises a base plate 59 riveted to the hood, provided at its vertical side edges with forwardly bent ears 60—60 supporting a transverse

pin 61, upon which there is pivotally mounted a lever member comprising side arms 62—62 and a transverse connecting portion 63, the side arms being rounded at their lower rearward edges to permit downward swinging movement, and being angular at their upper rearward edges to provide movement limiting abutment portions. A spring 64 is coiled about the pin 61 and bears at its respective ends upon the base plate 59 and the connecting portion 63 to normally retain the lever member in its horizontally disposed raised position, as indicated in Fig. 5. A transverse pin 65 is provided between the outer ends of the arms 62 adapted for engagement by the hook 28 of the hood catch. The lower portion of the base plate is offset, as at 66, and is provided with a resilient bumper 67, of rubber, or the like, and adapted to engage the barrel of the hood catch.

In operation the hook 28 is engaged over the transverse pin 65 of the lever member drawing the same downwardly and at the same time decreasing the lateral distance between the hood and said pin thus drawing the hood catch barrel inwardly against the bumper 67. The hood is thereby pressed inwardly and held under pressure against looseness and rattling, the hood at the same time being pulled downwardly by the downward pull of the hood catch.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters Patent is:

1. In a hood catch, a hold down clamp, a keeper including a movable member adapted to be engaged and moved by said clamp, and contact means hingedly connected thereto adapted upon said movement imparted thereto by the clamp to engage outwardly against said clamp, whereby an inward pressure is exerted on the hood to move the hood inwardly.

2. In a hood catch, a hold down clamp, a keeper including a movable member adapted to be engaged and moved by said clamp, contact means hingedly connected thereto, and means carried on the hood adapted to engage and cause movement of said contact means outwardly against the clamp whereby an inward pressure is exerted on the hood to move the hood inwardly.

3. In a hood catch, a hold down clamp, a keeper including a movable member adapted to be engaged and moved by said clamp, contact means hingedly connected at one end with said movable member and having a contact part at its other end, and fulcrum means carried on the hood engaging said contact means between said hinged end and

5 said contact part and adapted to cause movement of said contact part outwardly against the clamp, whereby an inward pressure is exerted on the hood to move the hood inwardly.

10 4. In a hood catch, a hold down clamp, a keeper including a movable member adapted to be engaged and moved by said clamp, contact means hingedly connected at one end with said movable member and having a contact part at its other end and cam means carried on the hood engaging said contact means and adapted to cause movement of said contact part outwardly against the clamp, whereby an inward pressure is exerted on the hood to move the hood inwardly.

15 5. In a hood catch, a hold down clamp, a keeper including a movable member adapted to be engaged and moved by said clamp, bumper means carried thereby, and means carried on the hood adapted to engage and cause movement of said bumper means outwardly against the clamp, whereby an inward pressure is exerted on the hood to move the hood inwardly.

20 6. In a latch for a closure, a base to which said latch is secured, a latch guide mounted upon said base, a latch body movable upon said guide, yielding means tending normally to move it downwardly along said guide, a member at the upper end of said latch body adapted to engage the closure and to direct pressure downwardly thereagainst and means, mounted between closure and latch, adapted to direct pressure inwardly against said closure in response to the downward pressure exerted by said latch.

25 7. In a latch for a closure, a base to which said latch is secured, a latch guide mounted upon said base, a latch body movable upon said guide, yielding means tending normally to move it downwardly along said guide, a member at the upper end of said latch body adapted to engage the closure and to direct pressure downwardly thereagainst and means, mounted between closure and latch, adapted to direct pressure inwardly against said closure in response to the downward pressure exerted by said latch, said means including a member movably mounted upon said closure.

30 8. In a latch for a closure, a base to which said latch is secured, a latch guide mounted upon said base, a latch body movable upon said guide, yielding means tending normally to move it downwardly along said guide, a member at the upper end of said latch body adapted to engage the closure and to direct pressure downwardly thereagainst and a movable member, interposed between closure and latch, adapted to receive the downward pressure exerted by said latch and to exert, in response thereto, lateral pressure inwardly against said closure.

35 9. In a latch for a closure, a base to which

said latch is secured, a latch guide mounted upon said base, a latch body movable upon said guide, yielding means tending normally to move it downwardly along said guide, a member at the upper end of said latch body adapted to engage the closure and to direct pressure downwardly thereagainst and a cam mounted on said closure and a member mounted upon said closure, movable across said cam, interposed between closure and latch and adapted to receive the downward pressure exerted by said latch and to exert, in response thereto, in association with said cam, lateral pressure inwardly against said closure.

40 10. In a latch for a closure, a latch body and means for imparting downward movement thereto, means at the upper end of said latch body for engaging the closure and for directing pressure downwardly thereagainst in response to downward movement of the latch body and means, interposed between closure and latch, for translating the downward pressure exerted by the upper portion of said latch body into inward pressure against said closure.

45 11. In a latch for a closure, a latch body and means for imparting downward movement thereto, means at the upper end of said latch body for engaging the closure and for directing pressure downwardly thereagainst in response to downward movement of the latch body and means, interposed between closure and latch, for translating the downward pressure exerted by the upper portion of said latch body into inward pressure against said closure, including a member movably mounted upon said closure.

50 12. In a latch for a closure, a latch body and means for imparting downward movement thereto, means at the upper end of said latch body for engaging the closure and for directing pressure downwardly thereagainst in response to downward movement of the latch body and means, interposed between closure and latch, for translating the downward pressure exerted by the upper portion of said latch body into inward pressure against said closure, including a member movably mounted upon said closure and a cam, mounted upon said closure, adapted to be engaged thereby.

55 13. In a latch for a closure, a latch body and means for imparting downward movement thereto, means at the upper end of said latch body for engaging the closure and for directing pressure downwardly thereagainst in response to downward movement of the latch body and means, interposed between closure and latch, for translating the downward pressure exerted by the upper portion of said latch body into inward pressure against said closure, including a member movably mounted upon said closure, and means for directing it outwardly against said latch.

14. In a latch for a closure, a latch member mounted adjacent said closure, and means for imparting movement to the latch member, a movable means mounted upon the closure, and adapted to move bodily, in relation to said closure, a member associated with said latch adapted to engage said bodily movable means and to impart to it a generally downward movement in relation to said closure, and means for directing a portion of said movable means, other than that engaged by said above mentioned portion of the latch, into thrusting engagement with another portion of said latch.
15. In a latch for a closure, a latch member mounted adjacent said closure, and means for imparting movement to the latch member, a member slidably mounted upon said closure, the latch member being provided with a portion adapted to engage the upper end of said slidable member, the lower end of said slidable member being adapted to engage a lower portion of said latch.
16. For use with an automobile hood closure, a latch including a latch member mounted adjacent said closure, means for guiding said member for movement along a generally upright axis, yielding means tending normally to impart to said latch member a downward movement along said guiding means, a movable member mounted upon said closure and a projection from said latch member adapted to contact said movable member, said movable member being adapted, when engaged by said projection, to exert a thrust against another portion of said latch member, at a point spaced substantially along said latch member from said projecting element.

Signed at Bridgeport, county of Fairfield,
and State of Connecticut, this 25th day of
July, 1928.

RAYMOND G. MOORE.
